W. L. SHEPARD,

ENGINE.

APPLICATION FILED JAN. 12, 1916.

1,263,475.

Patented Apr. 23, 1918

UNITED STATES PATENT OFFICE.

WILBUR L. SHEPARD, OF WEST HARTFORD, CONNECTICUT.

ENGINE

1,263,475.

Specification of Letters Patent. Patented Apr. 23, 1918.

Application filed January 12, 1916. Serial No. 71,778.

To all whom it may concern:

Be it known that I, WILBUR L. SHEPARD, a citizen of the United States, and a resident of West Hartford, in the county of Hartford and State of Connecticut, have invented a new and Improved Engine, of which the following is a specification.

My invention relates more especially to the class of engines more commonly known as explosive or gas engines, and an object of my invention, among others, is to provide an engine in which the maximum power shall be obtained with a given expenditure of fuel.

One form of engine embodying my invention and in the construction and use of which the objects herein set out, as well as others, may be attained, is illustrated in the accompanying drawings, in which—

Figure 1 is a view in central vertical section through an engine embodying my invention, the plane of section extending lengthwise of the crank shaft.

Fig. 2 is a view in side elevation, partially in section, on plane denoted by dotted line 2-2 of Fig. 1.

The engine forming the subject matter of this application embodies the broad idea expressed in my copending application filed March 25th, 1916, Serial No. 86,698, and which contains claims to the broad idea, a specific arrangement of the mechanism only being claimed herein. In the present case I have adapted the invention to an arrangement in which the cylinders are disposed on diametrically opposite sides of a crank shaft. It will be understood that any number of cylinders may be employed, and while the device contemplates fixed cylinders and a rotating crank shaft, the idea may be readily embodied in a reversed arrangement of such parts in which the crank shaft may be stationary and the cylinders may revolve.

The construction herein shown is such that it may be applied for use in aeroplanes and the like, the numeral 5 indicating a base or crank case with radial arms constituting cylinders 6, an intake chamber 7 being located in said base or case and opening into each of the cylinders. An intake passage 8 extends along the body of one of the cylinders from a carbureter 9 of any ordinary construction and operation for mixing the fluids and delivering them for use within the cylinders. Brackets 10 extend from the sides

of two of the cylinders in position to receive standards of any suitable form for supporting the engine, said support also comprising a standard 11 within which the crank shaft 12 has a bearing, the opposite end of the shaft being supported in any suitable manner. The crank shaft, extending through the crank case 5 and having suitable bearings therein, is provided with a crank 13 located within the intake chamber 7.

A piston 14 located within one of the cylinders has a pitman 15 pivotally connecting it with the crank 13, said pitman being pivotally connected to the piston. This pitman has radially extending arms 16 disposed about the crank 13, a pitman 17 pivotally connecting each arm with a piston 18 located in each of the other cylinders.

An intake valve 19 is located in an opening in the head of each piston to control the flow of fluid through said opening to the explosion side of the piston, these valves being operated by the difference in pressure upon opposite sides of the piston in a well known manner to properly regulate the flow of fluid. Exhaust valves 20 secured to valve stems 40 are located in the head of each cylinder to control the flow of the fluid after the explosion takes place. These valves have a movement in a direction across the axis of the cylinder, or at substantially right angles to said axis. This is of special advantage, in a construction in which the cylinders are caused to rotate, as in such case their opening and closing movements will not be affected by centrifugal force. Valve operating levers 21, of bell crank form, are pivotally mounted upon the sides of the cylinders, these levers each including a shaft 41 to which one forked arm is secured and connected with a valve stem to operate it, and to which the other offset arm is secured and extends to and rests against a cam 22 loosely mounted on the crank shaft 12. This cam is so shaped that each lever will be operated to cause opening and closing movement of its exhaust valve at the proper time. The cam is driven as by means of an internal gear 23 meshing with a pinion 42 that meshes with a direction pinion 24 both mounted on studs on the side of the engine base or crank case, or of a cylinder, the pinion 24 meshing with a gear 25 secured to the crank shaft 12. An opening 26 in the base is closed by a cover 27 and serves as a

means of access to chambers in the cylinders and by means of which the parts may be assembled.

An impetus wheel 28 is secured to the 5 crank shaft 12, this wheel having a recess 29 in one face within which the cylinders are located. A rim 30 forming the boundary of this recess is provided on its inner surface with buckets 31 at the bottom of a groove in 10 the rim and located to travel in close proximity to an exhaust nozzle 32 extending, one from the head of each cylinder, and each having a passage controlled by an exhaust valve 20. The arms 33 of the impetus wheel 15 are of considerable width and are diagonally arranged so that a circulation is created by causing air to flow from one side of the wheel to the opposite side, which air is then passed across the cylinders and acts as a 20 cooling medium.

In the operation of this engine the gases are admitted to the cylinders and are ignited therein while the valves 20 are closed. The gases thus exert their force upon the 25 pistons to drive them forward, that is, to the opposite end of the cylinder from that to which the gases are admitted. Just as soon as the gases have acted to their utmost upon the pistons then the valves 20 are 30 opened and the gases are projected through the nozzles 32 on to the impetus wheel, thus exerting all of the forces remaining after they have acted upon the piston.

While I have shown and described herein 35 a satisfactory arrangement of mechanism embodying my ideas, this may be changed to a greater or lesser degree and yet be within the spirit and intent of the invention.

I claim—

40 1. An engine including a hollow crank case providing an intake chamber, cylinders radiating from said crank case and disconnected at their outer ends, a shaft rotatably mounted in said crank case, pistons located 45 in each of the cylinders and operatively connected with the crank shaft, an impetus wheel secured to the crank shaft and with its periphery surrounding and inclosing the ends of the cylinders and having buckets on 50 its interior, said wheel being closed entirely about its periphery and an exhaust head arranged to deliver the exhaust from the cylinders against said buckets.

55 2. An engine including a hollow crank case providing an intake chamber, cylinders radiating from said crank case and disconnected at their outer ends, a shaft rotatably mounted in said crank case, pistons located 60 in each of the cylinders and operatively connected in the crank shaft, an impetus wheel secured to the crank shaft and with its periphery surrounding and inclosing the ends of the cylinders and having buckets on its 65 interior and an exhaust head extending across the outer ends of the cylinders and

projecting on opposite sides thereof and having at one end an exhaust opening to deliver the exhaust against said buckets.

3. An engine including a hollow crank case providing an intake chamber, cylinders 70 radiating from said crank case and disconnected at their outer ends, a shaft rotatably mounted in said crank case, pistons located in each of the cylinders and operatively connected with the crank shaft, an impetus 75 wheel secured to the crank shaft, and with its periphery surrounding and inclosing the ends of the cylinders and having buckets on its interior, an exhaust head extending across the end of each cylinder and projecting 80 on opposite sides thereof, one end terminating in an exhaust nozzle to deliver exhaust against said buckets, a valve located in said head and with its stem located in the extension opposite said nozzle, and a valve 85 lever projecting through an opening into said extension and engaging said valve to operate it.

4. An engine including a hollow crank case providing an intake chamber, cylinders 90 radiating from said crank case and disconnected at their outer ends, said structure being formed of a single piece of metal and having a central opening on one side, a flanged plate closing said opening, a crank 95 shaft extending into said case and plate, pistons located in each of the cylinders and operatively connected with the crank shaft, an impetus wheel secured to the crank shaft and with its periphery surrounding 100 and inclosing the ends of the cylinders and having buckets on its interior, and an exhaust head arranged to deliver the exhaust from the cylinders against said buckets.

5. An engine including a hollow crank 105 case providing an intake chamber with an opening thereto, a flanged plate closing said opening and said chamber, a crank shaft having a bearing in said case and plate, arms radiating from said hub and disconnected at their outer ends and comprising 110 cylinders opening for their full dimensions out of said intake chamber, pistons located in said cylinders and operatively connected with the crank shaft, an impetus wheel having its periphery surrounding and inclosing the ends of the cylinders and with buckets on its interior, and exhaust heads secured to the ends of the cylinders to deliver exhaust against said buckets.

6. An engine including a hollow crank case providing an intake chamber, cylinders radiating from said case and disconnected at their outer ends, a crank shaft rotatably mounted in the crank case, pistons located 125 in the cylinders and operatively connected with the crank shaft, an impetus wheel secured to the crank shaft and having its periphery surrounding and inclosing the ends of the cylinders and with buckets on its interior, 130

exhaust heads at the ends of the cylinders having openings extending at right angles to the axes of the cylinders, said openings each constituting an exhaust chamber, a 5 valve stem extended across the exhaust chamber of each exhaust head, a valve located on one side of each exhaust chamber,

a shoulder located on each stem and on the opposite side of the exhaust chamber from the valve, a valve lever extending through 10 an opening in each exhaust head and in engagement with said shoulder, and means for operating each lever.

WILBUR L. SHEPARD.
